 tion of Massachusetts

Application June 5, 1944, Serial No. 538,816

19 Claims. (Cl. 51—33)

1

This invention relates to an apparatus for grinding a non-rotatable work piece and especially for grinding billets and other shapes substantially automatically.

After an ingot has been rolled into billets and the latter heated in a soaking pit, it is found that the billet has a decarburized surface layer which may have other defects, such as cracks. This layer must be removed before various types of products can be made therefrom; and one aspect of this present invention relates to its removal by a grinding operation. It is customary to grind off the surface portion of a billet by means of a swing frame grinder operated manually. This operation has involved back-breaking labor and the waste of considerable time and expense.

The primary object of this invention is to provide an apparatus for grinding off the surface layer of billets and the like by means of a grinding wheel which is so arranged and operated that the layer may be removed almost automatically and with a minimum of attention and effort on the part of the operator.

Another object is to provide a grinding apparatus in which a grinding wheel carried on a movable frame is held automatically under pressure, and especially a yielding pressure, against a work surface of irregular contour.

Another object is to provide an apparatus of this type in which the grinding wheel may be oscillated to improve the grinding action.

Another object is to provide a grinder for billets and the like in which the work is subjected to the action of a series of relatively stationary wheels so arranged as to remove the entire work surface.

Other objects are to provide adjustments and compensating features which make machines of this type capable of satisfying many requirements. Further objects will be pointed out or made apparent in the following disclosure.

In accordance with one aspect of this invention, I propose to grind off the surface layer of a longitudinally movable but non-rotatable work piece by means of a grinding wheel mounted with its axis parallel with the direction of work travel. For a wide work piece, a plurality of wheels may be arranged to cut parallel paths; and the wheels may be offset so that they do not interfere with one another and the work is introduced into each grinding zone progressively. Each wheel is held against the work under pressure which may be varied. Also, for grinding billets, it is preferred to oscillate each wheel through an angle which apexes at the work surface. It is also preferred that the work be passed progressively through the

2

machine by driving mechanism which permits or provides for several passes of the work through the grinding zone, and preferably which automatically turns the work over after each pass to bring a new surface into contact with the wheel or wheels.

Referring to the drawings which illustrate a preferred embodiment of the machine as applied to grinding billets by a succession of abrasive wheels, the figures are as follows:

Fig. 46 is a fragmentary front elevation of that part of the machine which is indicated by the arrowed lines 46 of Fig. 9 showing the manual control lever and its stops which position the work deflector; and

Fig. 47 is a fragmentary sectional view of the adjustable deflector for the billet taken on the line 47-47 of Fig. 9.

20 Referring first to Figs. 1 to 5 inclusive, I have there illustrated my method diagrammatically.

As shown in Figs. 1 and 2, billets 12 are successively transferred from a loading platform 13 onto a set of freely rotatable supporting conveyor rolls 14 and then moved onto a set of power driven rollers 15 which carry the billets endwise beneath a set of grinding wheels 16. These wheels have their axes parallel with the direction of travel of the work and so grind a

30 narrow grooved path along the work. A set of pressure rolls 17 beneath the billet serve to hold the grinding wheels in grinding contact with the work. According to a primary feature of this invention, the grinding wheels 16 are not in axial

35 alignment; but they are offset in a diagonal relationship relative to the line of travel of the work. That is, the first grinding wheel of position 1 (Fig. 1) will grind an elongated, transversely arcuate path indicated by the numeral 1 in Fig. 3;

40 while the wheel of position 2 (Fig. 1) is offset so that it grinds the path 2 of Fig. 3. Each grinding wheel grinds a path contiguous to and preferably overlapping the path of the adjacent wheels; and the wheels in positions 1 to 9 cover

45 the entire surface, except the corner portions. The grinding wheel in position 10 is offset from the other wheels 16 (Fig. 1) and so positioned that it grinds one corner of the billet as indicated at 10 in Fig. 3. This grinding operation is

50 accomplished by abrasive wheels which are axially stationary, except as they may be oscillated through a suitable angle as diagrammatically shown by the dotted lines in Fig. 2 and later described. When the billet 12 has passed the last

55 wheel 10, it is deflected by suitable mechanism at the left hand end of the machine to the position 18 where it is transferred to the position 19 (Fig. 1) and it is then returned by a succession of rolls 20, preferably arranged as an inclined

60 gravity conveyor system, to the position 21 where it may be either manually or mechanically moved back, such as by an elevator system, to the first grinding position for passing again through the machine. At this time, the billet is turned over,

65 preferably through a quarter turn, to present a second face for grinding. Thus the billet is carried on through the grinding zone four times for a four faced work piece; and after the final grinding operation, the work deflector is rendered inoperative and the work 12 is caused to

70 pass from the machine.

The procedure may be widely varied. As indicated by the arrows in Fig. 4, the work piece

75 12 may be started at position 24 and traversed in grinding contact with the entire set of grinding

wheels to the position 25 where the work piece is turned over through a quarter turn. Then, by reversing the power driven supporting rolls 15, it is traversed back through the same succession of abrasive wheels to the starting position 26 where the work is again turned over. Thus, it is ground during each traverse as it goes from positions 24 to 28 and completed at the normal loading end of the machine. In the arrangement shown in Fig. 5, the work is traversed and quarter turned as shown by the arrows. In this procedure, it starts at position 29 and is finished in position 30 at the same end of the machine.

This process may be carried out by various types and arrangements of mechanisms, but I prefer to employ the procedure of Figs. 1 and 2 and the construction illustrated in the remaining figures of the drawings. The entire assembly of the machine is shown in Figs. 6, 7, 8 and 9 which are to be viewed in an end to end relationship in the order of the figure numbers starting at the right hand end of the machine. In this machine, the billet 12 loaded onto the platform 13 (Fig. 6) is suitably moved onto the freely movable rollers 14 and then manually or mechanically conveyed endwise along these rollers towards the left where it is brought onto the power driven rollers 15 (Figs. 10 and 39) located in the two intermediate sections of the machine, shown in Figs. 7 and 8. There, the billet 12 is moved longitudinally while its top face is subjected to the abrading action of the grinding wheels 16 in the positions 1 to 10 of Figs. 1, 2 and 3. Ultimately, the billet 12 is traversed by the roller driving mechanism on its final pass to the left hand end of the machine where it is diverted into the position 18 (Figs. 1 and 2) by an adjustable deflector 34 (Fig. 9). The billet 12 slides down an inclined chute 35 (Fig. 45) which may be provided with free rollers. The rolls 20 then serve to return the billet under the influence of gravity to the position 21 (Fig. 1) where it strikes a lengthwise adjustable deflector plate 36 (Fig. 6) and is thrust into engagement with prongs on an elevator conveyor chain 37 (Figs. 6 and 44) which thus returns the billet 12 to the starting position and at the same time turns it over for a second grinding operation.

The work driving mechanism at each of the stations 1 to 9 inclusive, not including station 10, is illustrated in Figs. 10, 11 and associated figures. As shown in Fig. 10, the billet 12 passes from the first set of free rolls 14 into engagement with the first power driven roller 15, thence over a free roll 39 (Fig. 43) which is similar to the roll 14, and then over the pressure roller 17 beneath the grinding wheel 16. The pressure roller 17 is vertically movable in such a manner that the weight of the billet serves to hold the abrasive wheel down in grinding contact with the top surface of the billet. The billet 12 travels then onto another power driven roll 15 and so on along this succession of rollers through the grinding stations 1 to 10.

Although various types of grinding apparatus may be employed within the scope of this invention, a construction of the general type known as a swing frame grinder may be utilized because of the flexibility of adjustment and the ease with which the grinding wheel may be oscillated or tilted through a desired arc. As illustrated in Figs. 11 and 12, the grinding wheel 16 is removably mounted on suitable roller bearings (Fig. 31) carried in a hood 40 having a demountable part arranged for installing the driving belts. The

hood is mounted on the end of a tube 41. The tube is pivoted on a universal ball joint 42 (Fig. 11) journalled on a trolley support 43 arranged to carry the swing frame grinder. To the right of the ball joint 42 is mounted an extension frame 44 supporting and clamping a motor slide 45 (Fig. 17) carrying a constant speed electric motor 46. The grinding wheel 16 is driven by the motor 46 by means of two V belts 47 running over a V pulley 48 on the grinding wheel mount (Fig. 31) and a two-stepped reversible pulley 49 (Fig. 11) keyed on the shaft of the motor 46. The V pulley 49 is reversible so as to take up for grinding wheel wear and to provide a higher R. P. M. for the smaller sized wheel. The motor slide 45 (Figs. 11 and 17) has an integral depending threaded lug 50 engaging a flanged screw 51 which is rotatably mounted in a slotted stationary integral lug on the extension frame 44 and arranged to move the motor 46 rearwardly and hold the V belts 47 tight. Each of the electric motors 46 for the different grinding stations have individual push button switches 52 (Fig. 10) conveniently mounted near the other electrical control apparatus.

It is desirable to prevent the forward end of the billet 12 from striking the side of the grinding wheel 16. This is accomplished by a spring pressure mechanism shown particularly in Figs. 10 and 11, which holds the wheel out of the way and permits the weight of the billet to pull the wheel down into grinding contact. The pressure roller 17 is normally positioned by a spring 54 (Fig. 11) so that the high point of its periphery is somewhat above the plane of travel of the bottom face of the billet 12. When the billet 12 strikes the periphery of the roller 17, it forces the roller downwardly against the pressure of the spring. The roller support 55 carries the sleeve bearings supporting the pressed on journal shaft 60 of the pressure roller 17. The support 55 is connected to cause a compression spring 56 to move downwardly a vertical slide frame 57. The frame is connected through a pivot pin 58 with a tilting or rocking frame 59 which pivotally supports an extension of the hood 40.

The support 55 is fixed on a depending tube 61 of square cross section (Figs. 11 and 13) which is positioned by means of two pairs of flanged rollers 62. Each roller 62 is journalled on a shaft 63 carried between a pair of brackets 64 secured on the inner sides of I beams 65 of the framework. The I beams 65 are attached to plates 66 which are secured to the concrete foundation for the machine. The pressure of the spring 54 is adjusted by means of a flanged screw 67 threaded into a square plate 68 sliding within the square tube 61 and engaging the top of the spring 54. The flange of the screw 67 supports the member 55. It is adjusted by an integral extension having a square top for a wrench. An adjustable screw 69 secured to the support 55 and freely movable through an opening in the top of the front I beam 65 serves to limit the upward motion of the support 55. A screw 70 is adjustably carried in the top of the support 55 and engages the underside of the mount 71 which carries the pivot pin 58, and which is integral with the vertical slide frame 57. This serves to limit the downward movement of the slide frame 57 and the grinding wheel 16. The pressure of the spring 56 in the slide frame 57 may be also adjusted to obtain proper grinding action by means of a screw 72 actuated by a sleeve nut 73 suitably secured in a bottom plate of the slide 57. The

screw 72 has an integral square shaped head which slides in the frame 57 and supports the bottom of the spring 56.

Although the method of grinding and the apparatus may be employed without oscillating or tilting the wheel 16, I preferably oscillate the wheel through a suitable angle such as 15°, and this is permitted by the pivot pin 58 connecting the frame parts 57 and 59. The axis of the pivot pin 58 is substantially aligned with the top face of the billet during grinding. The rocking frame 59 is a U shaped member having side slide straps 74 (Figs. 11 and 12) which form guides for the vertically movable two piece slide 75 that pivotally mounts a swivel guide 76 (Fig. 12) having an aperture which slidably but non-rotatably engages, by means of a fixed key, a guide bar 77 secured onto the hood 40, so that the grinding wheel 16 will tilt with the rocking frame 59.

The wheel 16 is fed towards the work as it wears away by means of a handwheel 85 operating a screw 86 passing through the threaded top plate 87 (Fig. 11) suitably connected to the slide 75 which carries the swivel guide 76. The latter (Fig. 12) allows the guide bar 77 to telescope therethrough as the grinding wheel 16 becomes smaller in diameter, or when its grinding station is changed.

The rocking frame 59 is oscillated by means of a pin 88 carried by the plate 87 (Fig. 11) and engaging a vertical slot in a slide bar 89 connected to a lever 90 (Fig. 10) fulcrumed to a bracket 91 and connected by a link 92 to the slide bar 89. The lever 90 is oscillated by a link 93 connected to an eccentric 94 mounted on the shaft of an electric motor 95. This driving mechanism may be of suitable construction, such as a double reduction direct current gear motor which drives at a constant or adjustable speed. The motor is controlled by a push button switch 96 (Fig. 10) and a suitable rheostat 97 which thus controls the rate at which the grinding wheels are oscillated. The degree of oscillation may be controlled by using an adjustable variable throw eccentric.

By this construction, the rocking frame 59 that guides the grinding wheel 16 may oscillate for tilting the wheel as required without affecting the vertical movement of the slide frame 57 and the support 55 or the pressure roller 17. Before the grinding wheel comes into contact with the pressure roller, the spring 56 positions the grinding wheel above the normal plane of contact with the billet 12, and the wheel continues to oscillate in that position. When the billet pushes down the pressure roller 17, this forces the rocking frame 59 downwardly and brings the wheel into contact with the top of the work and causes it to grind an arcuate path on its top face as the billet progresses through each grinding zone. The contact of the wheel with the work is under the resilient pressure of the spring 56 so that the wheel 16 cannot be forced into the work at too rapid a rate.

The grinding wheel is secured in one of the positions 1 to 10 by mechanism shown particularly in Fig. 11. The support 43 which journals the ball joint 42 of the swing frame grinder is constructed like a trolley and is carried on the trolley rails 101 formed by the two bottom flanges of a trolley I beam 102 suitably carried on the framework over the rear of the machine. As shown particularly in Figs. 11, 21, 22 and 23, the trolley comprises two separate plates 104 integral with the support 43. These plates 104 carry the four flanged trolley wheels 105 which

are guided and ride on the rails 101 of the I beam. Two rollers 106 (Figs. 11 and 22) suitably pivotally carried by the plates 104 are adjustably positioned against the under side of the trolley rails 101 and prevent lifting of the support 43 under the pressure of grinding.

The position of the grinding wheel relative to the billet is controlled by a roller 110 (Figs. 11 and 18) mounted to ride against the rear side 5 of the billet. The roller 110 is carried by an inverted L-shaped roller mount 111 adjustably secured on an integral depending projection on a slide 112 so that, as shown in Fig. 19, it may be moved vertically in relation to the side of the billet 12. A projection on the slide 112 is bolted to the roller mount 111 by means of two bolts mounted in elongated slots. The slide 112 is slidably mounted by means of a gibbed slideway on the intermediate slide 113 and there locked in position by suitable set screws. The slide 113 has an integral top slide 115 also mounted within a gibbed slideway 116 which is integral with a forwardly extending arm 117 fixed to the lower half of the support 43 carrying the ball joint 42. By this mechanism, the roller 110 may be adjusted to cause the grinding wheel to grind in any of the positions 1 to 10, and since the roller 110 is positioned by the side of the billet, these paths will have a definite relationship.

30 The adjustment of the grinding wheel across the face of the work 12 to these various positions is made first by crudely adjusting the position of slide 112 relative to its supporting slide 113. The fine adjustment is made by a screw 120 (Fig. 11). This screw is rotatably mounted in a slotted portion of the plate attached to the slideway 116 and engages a threaded integral connection between the slide 113 and the top slide 115 which is thereby adjusted relative to the slide 116. The support 43 is moved toward the left by means of two compression springs 125 carried in two separate housings 126 which are secured by set screws 127 to the trolley rails 101 of the I beam. The trolley plates 104 (Fig. 45 23) engage two separate plungers 128 slidably urged toward the left by the springs 125. The tension of the springs 125 is governed by the positions of the plungers 128 which project through two separate rear plates 129 of the housings 126, and are held by means of the two separate lock sleeves and nuts 130. The springs 125 push the plungers 128 and support 43 towards the left and thereby maintain the roller 110 against the billet 12.

55 Two separate stops 133 (Figs. 11, 23 and 25) are adjustably positioned on the trolley rails 101 and thus limit the movement of the trolley plates 104 toward the left. If there is no billet beneath the grinding wheel, then the support 43 and grinding wheel 16 will move toward the left until the trolley plates 104 abut the stops 133. When a new billet 12 passes through and contacts the roll 110, it moves the grinding wheel 16 back into the correct position to grind according to the adjustments, and the springs 125 will hold the grinding wheel 16 in its proper path. If it is desired to increase the tension of the springs 125, the lock sleeve 130 is moved forward by its adjusting nut until it touches the rear plates 129, then by further adjustment the springs 125 are compressed to increase their pressure. By loosening the clamping screws 127 the plungers 128 may be moved forward into contact with the trolley plates 104. When this has been accomplished, the clamping screws 127 are tightened.

rophosphate and the remainder of the ethyl cellulose solution are added and agitation is continued until a uniform mixture results. Thereupon the product is dried under vacuum at about 170° F. to remove the ethyl cellulose solvent vapors. The material is screened through a 20-mesh sieve to form a granulation and stored until used.

The observations relative to the action taking place at the various stages and the ingredients and amounts noted previously in connection with ascorbic acid are similarly applicable here.

In an alternative method, all of the ingredients of the B complex formulation above noted, except the ethyl cellulose, are ground to a uniform mixture and stored for use. In this alternative method the B vitamins are not coated and in some embodiments of the invention this is not necessary if the other means of achieving isolation and protection are utilized.

Iron coating and granulation

	Kilos
Sodium iron pyrophosphate	21.333
Ethyl cellulose dissolved in ethyl alcohol to make a 5% solution	.907
Calcium pyrophosphate	27.216

The sodium iron pyrophosphate is added to a mixer and coated with the ethyl cellulose solution as described above in connection with the foregoing granulations. After thorough coating, the calcium pyrophosphate is added gradually, and agitation is continued until mixing is complete. The resulting moist material is subsequently passed through an oscillating granulator and dried at 160° F. in air. The material may be sieved through a 60-mesh screen and stored for use.

The observations as to the actions taking place at the various stages, as well as the ingredients used on their amounts noted above in connection with the B and C granulations are also applicable to the iron granulation.

Iron-calcium-gelatin granulation

	Kilos
Calcium pyrophosphate	184.3
Coated iron granulation (described above)	49.456
Water-soluble binder dissolved in water to make 24 gallons	20

The calcium pyrophosphate and coated iron granulations are added gradually with the binder solution to a mixer until all of the materials have been added. The final product is a caky and cohesive mass, and may be passed through an oscillating granulator and dried in an oven at 160° F. In the final step the material is passed through a 20-mesh sieve and thereupon is stored for processing.

The binder is included so that the tablet will hold together during the stamping and coating operations. The amount used and the amount of water used are not critical as long as the desired result is obtained.

The amount of calcium pyrophosphate is that necessary, in addition to that used in the previously described granulations or mixtures, to achieve the desired amount of calcium in the complete mixture.

If desired, the iron may not be included in this granulation in which event only the calcium pyrophosphate and the binder would be granulated. The preferred method described, however,

has several advantages from the procedural standpoint.

All of the above ingredients, granulations or mixtures, depending on exact method selected for processing the various ingredients, are placed in a mixer from which the air may be evacuated. All of the materials are thoroughly mixed. After initial mixing and during continued mixing, the oil-soluble vitamins, such as A and D, in the form of a concentrate or in an oil, are sprayed over the granulation. If desired, the concentrate may be applied to one or a mixture of two or more granulations and the remaining materials then added. The addition of the concentrate in the preferred manner, however, has the advantage of obtaining a thorough mixture during the addition.

Flavoring material may also be added, before, after, or during the addition of the concentrate.

The complete mixture is then ready for stamping into tablets. In the specific illustrative example the amount in each tablet would be adjusted so as to make a million tablets.

The completed tablets are given a series of protective coatings. The first of these coatings may comprise a solution of a cellulose ester or ether, such as ethyl cellulose or collodion. If the tablet has any voids into which air may penetrate, the coating penetrates into such voids thereby eliminating and excluding air.

Although this material resists air and moisture, as has been pointed out heretofore, X-ray analysis shows that the coating is sufficiently penetrated under conditions prevailing in the alimentary canal to permit disintegration of the tablet and the release of all of its constituents for utilization by the body. The second coating may consist of a cellulosic solution with which a vegetable shellac has been mixed. This second coating may be repeated any number of desired times, for example four additional coats have been found to be desirable. The substitution of a part of the cellulosic material by shellac is desirable from the dietary point of view, but either may be used. It is desirable to dust each of the coatings with a calcium salt in order to facilitate the coating. This also permits the inclusion of a larger amount of calcium in the tablet.

If desired, one or more of the coatings may be dusted with an acidic material or with a calcium compound containing the same, such as for example, citric acid.

Following the coatings with cellulosic material and shellac, it may be desirable to coat the tablets with a gelatin and sugar solution as is conventional in the tablet coating art.

Following this treatment the tablets may be waxed with a solution of wax in a suitable volatile solvent to provide a polished surface, as is conventional in the tablet coating art.

Although the use of antioxidants and other additional agents is not necessary in forming the tablets of the present invention, it is to be understood that the use of such materials is not excluded.

As illustrative of the effectiveness of the protection against loss of potency afforded by the coating of ethyl cellulose, vitamin tablets were prepared following the general technique described above, including the application of a final sugar coating. Immediately upon their completion the vitamin tablets were analyzed by conventional quantitative analysis techniques to determine the vitamin A content as expressed in 75 U. S. P. units, and the vitamin B₁, vitamin C,

167 (Fig. 10) to regulate the speed of traverse of the billets 12 to obtain the desired grinding results. The motor 165 drives a spur gear 170 meshing with a spur gear 171 mounted on a shaft 172 which mounts at its forward end a bevel gear 173 arranged to drive a bevel gear 174 keyed to a two piece shaft 175 (Fig. 7) coupled together and which is suitably mounted in bearing brackets 176 (Fig. 11) arranged lengthwise of the machine on the rear I beam 65. The shaft 175 carries a set of bevel gears 177 which, with the bevel gear 174 drive the bevel gears 178 (Fig. 39) on the short shaft 179 suitably mounted in sleeve bushings in the unit. Each shaft 179 has a power driven roller 15 pressed into position for feeding the billet 12 endwise.

A pair of rollers 180 and 181 (Figs. 39 and 40) are also mounted in suitable bearings to rotate freely about vertical axes and engage the vertical sides of the billet 12. The right hand roller 180 20 is preferably mounted in fixed bracket, while the left hand roller 181 is preferably carried in a movable slide 182 (Fig. 40) to compensate for variations in the width and shape of the billet. The roller 181 is held under the pressure of an adjustable spring 183 to counteract the thrust of the springs 125. The spring is suitably mounted in the slide 182 and tightened by a suitable adjustable screw supported by a two part bracket 184. The rolls 180 and 181 position the billet relative to the grinding wheel.

A pressure roller 185 engaging the top of the billet (Figs. 39 and 42) is pressed on a shaft 186 having a horizontal axis which is rotatable in sleeve bushings in a slide block 187 which is freely movable vertically in a slideway formed by the two separate upright frames 188. A spring 189, which counteracts the upward pressure of the spring 54, presses against the slide block 187, and its tension may be suitably adjusted by a 35 check nutted screw 190 threaded in a top plate that connects the frames 188. It will thus be seen that these four rolls located in the upright frames 188 position the billet as it moves through the machine. This construction as above described is duplicated at each side of the grinding stations.

When the billet has passed the last grinding wheel and reaches the final position of Fig. 9, the leading end of the billet 12 strikes the deflector arm 34 (Figs. 45, 46 and 47) which is arranged at such an angle as to shove the billet to the position 18 (Fig. 1) where it slides down the incline chute 35 (Fig. 45). The deflector arm 34 is shown at the maximum adjustment, at which position the billet 12 still has a slight clearance in the opening formed by the upright frames 188 (Fig. 40) as it is skewed and fed by the power driven roller 15 and fulcrumed on the fixed roller 180 in the last work feeding station. The deflector arm 34 may be made movable to and from an operative position by pivoting it on a pin 200 suitably carried on a fixed bracket 201 mounted on the front I beam 65. A lever 202 is pivotally connected at right angles to the deflector arm 34 by means of a pivot pin 203. The lever 202 is held in a slotted pivotally mounted lug 204 (Figs. 9 and 47) on a movable bracket 205 which is adjustably mounted by means of an elongated slot (Fig. 9) and two bolts engaging the supporting front I beam 65 to vary the angle of the deflector arm 34. When the deflector arm is in the full line position of Fig. 9, the billet is deflected onto the chute 35, but when the deflector arm 34 is moved so that the lever 202 is in the

10 dotted line position of Fig. 9, it engages a slotted lug 206. Then the deflector arm 34 lies out of the path of the billet and the latter passes onto a further set of free rollers 206 outside of the machine. By lifting the lever 202 (Fig. 47) whose position is limited by the upper corner which strikes the mounting for the pin 200, it may be moved from engagement with the right hand angularly adjustable lug 204 and the deflector arm 34 is then thrown to an inoperative position when the lever 202 engages the slot in the lug 206. The outer sides of the slots in the lugs 204 and 206 are much higher than the inner bevelled sides, thereby limiting the swing of the lever 202. This permits the billet to be moved endwise from the machine onto the free rollers 206 which carry it to the next operation. Before the billet reaches the deflector arm 34, it is supported on the freely rotatable rollers 208, some of which may be power driven, which are mounted on the I beam 65 and have the same construction as shown in Fig. 43. An angle iron 207 is mounted near the rollers 208 (Fig. 45) to serve as a guide for the billet 12 before it strikes the deflector arm 34.

When the billet has slid down the chute 35 (Fig. 45) it comes to rest against an angle iron 210 which extends to the adjustable deflector 36. The billet is now in position on the rollers 20 to be moved back toward the starting end of the machine. Likewise, an angle iron 211 which guides the billet 12 extends from the first roller 20 under the framework (Fig. 8) at the left end to just beyond the electric motor 46 for the third grinding station (Fig. 7). Thereafter a flat plate 212 is used to allow the billet 12 to swing when it engages the deflector 36. These rollers may have certain ones power driven or they may be arranged in an inclined position, as indicated in Fig. 2, so as to act as a gravity conveyor system with a horizontal section beyond the right hand end of the guide 211 (Fig. 6).

When the billet reaches the starting end of the machine, it is deflected by the arcuate and adjustable deflector plate 36 (Fig. 6) into a position where it may be seized by the prongs 215 of the endless conveyor chains 37, shown particularly in Figs. 6 and 44. The conveyor chains 37 are mounted on sprockets 216 and 217 carried on two suitably mounted parallel shafts 218 and 219. The shaft 218 is adjustably mounted to take up the slack of the conveyor chains 37, and it is driven by a double reduction direct current gear motor 220 adapted for a constant or an adjustable speed. The motor may be controlled by a push button switch 221 and an adjustable rheostat 222 (Fig. 44) to regulate the speed of the conveyor chains 37 to lift the billet 12. The electric motor 220 drives a sprocket 223 which drives a link chain 224 which runs on a sprocket 225 keyed on the shaft 218 (Fig. 44). Various other features of construction and adjustment may be employed in connection with this elevator mechanism as well as the motor drives of the machine, as will be readily apparent to one skilled in the art.

The upper chain sprockets 217 mounted on the shaft 219 of the lifting conveyor are elevated somewhat above the working level of the grinding wheel, and the parts are so arranged that when the billet is discharged from the pronged elevator chains it will be turned through a quarter turn so as to present a new face to the grinding wheels. The billet is pushed by the prongs 215 of the conveyor chains 37 along the receiving chute toward the face rollers 14 (Figs. 6 and 44). At this point the operator may manually pull the billet onto

the rollers 14 and finally beneath the grinding wheel. It may be fed automatically by means of power driven rolls to the first grinding station if desired. This sequence of operations goes on until the four sides of the billet have been ground, and then the operator causes the billet to be discharged from the machine by swinging the deflector arm 34.

It will now be appreciated, in view of the description of a billet grinding machine, that various aspects of this invention may be employed in simplified types of grinding machines. For example, a single swing frame grinder may be used for grinding or snagging the surface of a casting, and wherein the grinding wheel is forced under a controlled pressure against the work surface without the operator having to apply effort on his part. This is accomplished by using a construction of the type shown primarily in Figs. 11 and 26, wherein the wheel is mounted for a reciprocating or a universal movement over a stationary or a movable work piece. The work may be reciprocated by the mechanism indicated in the drawings, and the wheel may be reciprocated crosswise of the work by suitable power connections to the trolley or manually by means of the rod 145 of Fig. 26.

Also, in such a simplified construction, the grinding wheel may be oscillated through an angle which apexes on the work surface, so that one may accomplish automatically the present day practice in which a workman swings manually a swing frame grinder in such a way as to give a tilting and sweeping action of the wheel across the work. Furthermore, a work piece having an irregular contour, such as a billet or a casting, may be safely ground without applying undue pressure on the grinding wheel, since the vertically movable and pivotal frame 57, 14 which controls the oscillation and up and down movement of the grinding wheel is so constructed that the grinding wheel may move in accordance with the work contour as permitted by the springs which control its position and so will not be forced too deeply into the work.

A further important feature in such machines wherein the grinding wheel axis is parallel to the direction of travel of the work lies in the fact that the work is not permitted to strike the grinding wheel as it approaches the same. An abrasive wheel is especially vulnerable to a blow on its side. In my preferred construction, the wheel is held away from the path of the work until the work itself causes the wheel to move forward into grinding contact. When a heavy work piece is being ground, I use the weight of the work itself to hold the wheel in that contact, although resilient means such as springs are provided which compensate for irregularities in contour of the work surface. In this way, I have provided a construction involving one or several swing frame grinders in which the highly difficult and objectionable operational features of that type of apparatus are eliminated, and the operator of the machine is required to do no more than minor operations and to control the various adjustments of the machine.

Accordingly, this invention applies both to a simplified type of machine involving one or a small number of wheels as well as a complex machine having a large number of wheels arranged to grind the entire path of a very wide piece of work in a single pass of the work through several grinding zones. For removing the surface layers of billets, these wheels are preferably arranged

5 to grind transversely of its travel of the work; but for some types of work it is entirely feasible to have the grinding wheel axis arranged at right angles to the direction of work travel and thus grind flat plane paths of the work surface.

10 The operations of these various parts of the mechanisms have been fully set forth above and need not be repeated. It will be understood that the machine operator may vary the operation of the machine widely in accordance with the various adjustments permitted in this construction.

15 It will also be appreciated that various mechanical equivalents may be substituted for the mechanisms above described, and that one may add other automatic features or eliminate some of those herein described without departing from the broad principles of this invention. Hence the above disclosure is to be interpreted as setting forth those principles and as describing a preferred embodiment of this machine and not as imposing limitations on the claims appended hereto.

20 I claim:

25 1. A grinding machine comprising power driven resiliently mounted rollers for supporting a non-rotatable long work piece and traversing it through a plurality of grinding zones, and power driven grinding wheels having their axes parallel with the direction of work travel which are arranged offset relative to each other in said zones for grinding simultaneously a plurality of parallel arcuate contiguous paths on one side of the traversing work piece.

30 2. A grinding machine comprising means for supporting a non-rotatable long work piece and traversing it progressively into a plurality of grinding zones, an independent power driven grinding wheel arranged in each of said zones for grinding one side of the work simultaneously, said wheels having their axes parallel with the direction of work travel and arranged offset relative to each other to grind parallel contiguous arcuate paths on one work surface during a single work traverse, means for holding each wheel resiliently against the work under a predetermined adjustable pressure, and means for oscillating the wheel through an angle apexed at the work surface which maintains the path of grinding substantially straight.

35 3. A machine for grinding the surfaces of non-rotatable long discontinuous work pieces comprising means for traversing a succession of said work pieces in one direction, a set of power driven grinding wheels arranged offset relative to each other and with their axes substantially parallel with the direction of travel of the work so as to grind simultaneously a plurality of parallel contiguous arcuate paths on one side of each work piece, and means for selectively removing any work piece or alternatively returning it in the opposite direction and again presenting it to the wheels for another grinding operation.

40 4. A grinding machine comprising power driven mechanism for traversing a long non-rotatable work piece endwise in one direction through a grinding zone, a series of grinding wheels arranged offset relative to one another for grinding simultaneously one face of the traversing work piece, mechanism for returning the work piece to its initial starting position and mechanism for turning the work piece to present another face to said wheels for a further grinding action.

45 5. A machine for grinding the surface of a

billet comprising mechanism for moving the billet endwise, a series of grinding wheels arranged with their axes substantially parallel with the direction of billet movement and offset relative to each other for grinding simultaneously a plurality of parallel arcuate paths, means for selectively removing the billet from the machine or alternatively returning it for another grinding operation and means for automatically turning the billet and presenting a new face for grinding during a second pass through the grinding zone.

6. A grinding machine comprising mechanism for traversing a work piece into and through a grinding zone, a grinding wheel arranged with its axis substantially parallel with the direction of travel of the work piece, and automatically actuated means which normally holds the side of the grinding wheel out of the path of the advancing work piece and which relatively moves the wheel and work into contact for the grinding operation as the leading edge of the work passes the side face of the wheel.

7. A grinding machine comprising means for traversing a work piece into and through a grinding zone, a power driven grinding wheel mounted to rotate about an axis which is substantially parallel with the direction of the movement of the work, means which normally holds the wheel out of the path of movement of the work as the latter enters the grinding zone and thereby prevents the work from striking the side of the wheel and means operated by the weight of the work entering the grinding zone which causes the wheel to move into grinding contact therewith.

8. A grinding machine comprising a grinding wheel arranged to grind an arcuate path on a work piece, means for traversing an elongated work piece parallel with the wheel axis, mechanism yieldingly urging the wheel away from its normal grinding position and means actuated by the forward end of the moving work piece which forces the grinding wheel forward and holds it in a resilient grinding contact with the work while the latter is traversing through the grinding zone.

9. A grinding machine comprising means for supporting a non-rotatable work piece and traversing it through a grinding zone, a power driven grinding wheel arranged with its axis substantially parallel with the direction of travel of the work piece, and means for oscillating the grinding wheel through an angle apiced at the work surface and maintaining its path of grinding substantially straight.

10. A grinding machine comprising a power driven grinding wheel, means for traversing a work piece in a direction parallel with the wheel axis so as to form an arcuate grinding path on the work surface, a pivotally mounted support arranged for oscillating the wheel about an axis passing substantially through the line of grinding contact and at right angles to the path of travel of the work, means for adjusting the wheel so that it will grind a pre-determined path, and automatically actuated means for oscillating the wheel during the grinding operation.

11. A grinding machine comprising a power driven grinding wheel, means for traversing a work piece in a direction parallel with the wheel axis so as to form an arcuate grinding path on the work surface, a pivotally mounted support arranged for oscillating the wheel about an axis passing substantially through the line of grinding contact and at right angles to the path of travel of the work, resilient means for holding the wheel under pressure against the work, and

automatically actuated means for oscillating the wheel during the grinding operation.

12. A grinding machine comprising a pivotally mounted frame, a grinding wheel rotatably mounted thereon and arranged for tilting through an angle apiced on the work surface, means for traversing a work piece parallel with the wheel axis so that the wheel grinds an elongated arcuate path, means for adjusting the frame to vary the wheel path, a swinging lever pivoted in substantial alignment with the work surface, means for adjustably connecting the frame to the lever so that swinging the lever tilts the wheel for any grinding position thereof and means for swinging the lever and oscillating the wheel through said angle.

13. A grinding machine comprising a pivotally mounted frame, a grinding wheel thereon arranged for tilting through an angle apiced at the work surface, means for traversing a work piece parallel with the wheel axis so that the wheel grinds an arcuate path, a lever pivoted on an axis passing substantially through the work surface, an adjustable connection between the frame and lever arranged to tilt the wheel through said angle for different sizes and paths of the wheel, means for oscillating the lever and said wheel, a resiliently mounted support for the pivot of the lever, and means actuated by entry of the work into the grinding zone which moves the lever support and causes the wheel to be held against the work under a yielding pressure.

14. A grinding machine comprising a swing frame grinder having a pivotal support, a motor and a driven grinding wheel mounted on opposite sides of the pivot, means for traversing a work piece in grinding contact with the wheel and substantially parallel with the wheel axis so that the wheel will grind an elongated arcuate path, means whereby the wheel may be moved transversely of the direction of work travel, and pressure means for holding the work and the wheel in grinding contact.

15. A grinding machine comprising a swing frame grinder having a pivotal support and a motor and a grinding wheel driven thereby mounted on opposite sides of the pivot, means for traversing a work piece in grinding contact with the wheel and substantially parallel with the wheel axis so that the wheel will grind an elongated arcuate path, means whereby the wheel may be moved transversely of the direction of work travel to adjust its path of grinding, means to adjust the position of the wheel to compensate for wheel wear, and means which holds the grinding wheel under yielding pressure against the work.

16. A machine of the type covered by claim 14 comprising a series of power driven rolls which move the work arranged alternately with resiliently mounted pressure rolls and means associated with the pressure rolls which holds the wheel in grinding contact with the work.

17. A grinding machine comprising mechanism for traversing a work piece in one direction, a trolley rail and a trolley movable thereon transversely of the direction of work travel, a frame universally pivoted on the trolley, a power driven grinding wheel carried by the frame with its axis substantially parallel with the direction of work travel and arranged to grind an arcuate path on the work, means associated with the trolley for moving the wheel and locating the wheel path, and means for oscillating the wheel through an angle apiced on the work surface.

17

18. A grinding machine according to claim 17 comprising means for adjusting the wheel position to compensate for wheel wear.

19. A grinding machine comprising mechanism for traversing a work piece into and through a plurality of grinding zones, a set of movable frames carrying independent power driven grinding wheels arranged in a series for grinding the work progressively in said zones, the wheels being substantially parallel axially with the direc- 10

18

tion of work travel and so arranged as to grind parallel, adjacent, arcuate paths along the traversing work, resilient acting pressure means controlled by the work for holding each wheel under a yielding pressure against the work and which compensates for variations in work contour, and adjustable means for varying the path of each wheel.

CARL A. CARLSON.
